INVENTOR
Philip H. Unsinger,
BY George D. Richards,
ATTORNEY

UNITED STATES PATENT OFFICE

PHILIP H. UNSINGER, OF MAPLEWOOD, NEW JERSEY

PACKAGE FOR SAFETY RAZOR BLADES

Application filed April 28, 1931. Serial No. 533,393.

This invention relates to an improved wrapper or package for safety razor blades, and has reference, more particularly, to a wrapper or package especially adapted to enclose a plurality of tongue-ended safety razor blades.

This invention has for its principal object to provide a novel construction of package or container for use in commercial distribution of safety razor blades, in which separable blade holding sections are provided having means to engage the endwise projecting tongues of the blade bodies so as to secure the same against displacement and against movement likely to bring the sharpened edges of the blades in contact with the folds of the wrapper enclosure with risk dulling such edges, while at the same time providing a novel interlocking relation of said blade holding sections calculated to segregate the blades one from another, while also assuring individual covering protection for each blade.

This invention has for another object to provide a razor blade enclosing package having in combination interfoldable individual blade holding sections and an external enveloping cover or wrapper for the same; the invention also has for an object to provide a novel form of blade enclosing package of the kind mentioned, from which individual blade holding sections may be readily removed at will by the ultimate consumer or user of the blades.

This invention has for a further object to provide a novel blade enclosing package which may be cheaply produced from paper, metal foil or other suitable material.

Other objects of this invention, not at this time more particularly enumerated, will be understood from the following detailed description of the same.

An illustrative embodiment of this invention is shown in the accompanying drawings, in which:—

Fig. 1 is a front face view of the closed razor blade package or wrapper according to this invention; Fig. 2 is a rear face view of the same; and Fig. 3 is a longitudinal section, taken on line 3—3 in Fig. 2.

Fig. 4 is a plan view showing the outer en-

veloping cover of the package opened to give access to the blade holding sections; and Fig. 5 is a similar view showing the first blade holding section unfolded ready to be torn away.

Fig. 6 is a plan view showing the blade holding sections of the package partially extended; and Fig. 7 is a longitudinal section through the same, taken on line 7—7 in Fig. 6.

Fig. 8 is a plan view of the blank of material from which the novel package is formed.

Similar characters of reference are employed in the above described views, to indicate corresponding parts.

Referring to said drawings, the reference character 10 indicates the razor blades adapted to be enclosed in the novel package of this invention. These blades are of the type possessing tongue-ends, that is tongue-portions 11 at their respective ends of a width less than the total width of the blade body. Said tongue-portions 11 form, with the ends of the blade body, shoulders 12 at opposite sides of the tongue-portions.

The novel blade holding and segregating means, comprises a longitudinal body of flexible material, such, for example, as paper, metal foil, or composite paper and metal foil material or other suitable material capable of being folded into the desired blade holding portion and the external envelope section. The blade holding portion comprises a strip of material having a width in excess of the length of the body portion of the blades 10 exclusive of the tongue-portions 11 thereof; said strip being divided by transverse folds to provide a plurality of transverse blade holding sections 13 of widths in excess of the width of said blades 10, and corresponding in number to the number of blades desired to be assembled and enclosed within the completed package. Integrally connected with the opposite ends of the respective blade holding sections 13 are infoldable flaps 14. Formed in these flaps 14, with one side thereof approximately contiguous to the line of fold whereby said flaps are joined to said holding sections 13, are rectangular openings 15 of dimensions 10c

slightly exceeding the dimensions of the tongue-portions 11 of the blades 10. Extending along the lines of transverse folds intermediate adjoining blade holding sections 13 are lines of perforations 16, whereby the material is weakened so that one blade holding section may be readily separated from another by tearing off the same if desired. While it is preferable to provide the 10 lines of perforations 16, it is not absolutely essential that the same be used, and therefore, from the broader aspects of this invention, the same may be omitted when desired.

Preferably the external envelope section 15 is connected with one end of the blade holding portion as an integral part thereof. Said envelop section comprises a sidewise flap section 17 intermediate its main body 18 and the inner end of said blade holding portion. 20 Said main body 18 is provided at its opposite end with an opposite sidewise flap section 19, and at its respective longitudinal sides with endwise flap sections 20 and 21.

To assemble the blades 10 with the blade 25 holding portion of the wrapper or package structure, the blade holding sections 13 are stretched out in longitudinal extension with the foldable flaps 14 opened out into the plane of said sections 13. The blades 10 are therefore 30 upon respectively superimposed upon the inner faces of said holding sections 13 so that the tongue-portions 11 of the blades register over the openings 15 of the extended foldable flaps 14. When the blades 10 are thus 35 positioned upon the holding sections 13, the foldable flaps 14 are thereupon inturned over the ends of the blade bodies in such manner that the tongue-portions 11 project through the openings 15 with shoulders 12 of the blade 40 bodies engaged against and within the folds 14' formed between said holding sections 13 and said foldable flaps 14. By the relation thus established between the blades and the holding sections 13 and their flaps 14, said 45 blades are securely held both against longitudinal and lateral shifting movements relative to the holding sections, and since the blade holding sections 13 and flaps 14 are wider than the extreme widths of the blade

50 bodies and lie over opposite faces of the blades in planes parallel thereto, the sharpened edges of the blades are fully protected against any direct edge-on contact with any portion of the holding member or covering 55 envelope, and consequently are not subjected to any risk of turning or dulling.

To enclose the assembled blades and holding sections into the enveloping external cover means, said holding sections are folded together, preferably in the zig-zag fashion indicated in Figs. 6 and 7, until the same overlie 60 one another as shown in Figs. 3 and 4, with the blade holding section 13 at the free end of blade holding portion inturned upon the 65 top of the pile of holding sections thus

formed. The folded up pile of blade holding sections is inturned over and upon cover flap section 17, which is thereupon inturned over and upon the inside face of the cover body 18, to dispose the pile of holding sections 70 therebetween. With the parts thus arranged, the opposite endwise flap 20 is overturned or infolded upon the flap 17, whereupon the other endwise flap 21 is overturned upon the infolded flap 20, and finally the remaining 75 sidewise flap 19 is inturned over said flaps 20-21. The meeting faces of said flap sections 19-21 are preferably adhesively secured together, thus firmly and securely retaining the cover means in enveloping relation to the folded up blade holding sections, or the cover flap sections may be otherwise secured in closed condition. The outer face of the main body 18 of the cover member may bear suitable advertising data, trade-mark or 80 trade-name description of the enclosed blades. 85

While I have shown the cover means integrally connected with the blade holding portion of the package, I do not desire to be limited to such arrangement, since the cover means may comprise an independent or separate envelope or other form of container to receive the blade holding portion. 90

It will be obvious that the user of the blades 95 may tear open the flap sections of the cover member, whereupon by unfolding the endwise flap 17 to expose the pile of blade holding sections, access may be had to the outer or end most holding section 13, which may be unfolded as indicated in Fig. 5 and torn off, if desired, through the line of perforations 16, the contained blade removed therefrom by unfolding the flaps 14 to give access thereto, whereupon the thus severed holding section 100 may be discarded, and the remaining holding sections with their contained blades refolded into the cover member until another blade is required, whereupon these operations are repeated until all the blades are 105 used. 110

From the above description it will be understood that a simple and yet efficient protective enclosing package for safety razor blades, and especially blades of the tongue-end type, is provided, both for use as a commercial distributing package as well as a container for the blades until the same are used by the purchaser. In its broadest aspect, the invention resides in the novel foldable blade holding means per se, regardless of the association therewith of the outer cover means, whether as an independent element or as an integral part thereof as shown; the latter arrangement being, however, from more specific aspects a part of this invention for which 115 claim is also made.

As changes other than those above indicated could be made in the above described constructions, and many apparently widely different embodiments of this invention could 120 125 130

be made without departing from the scope of this invention as herein described and shown, it is intended that all matter contained in the above description or shown in the accompanying drawings shall be interpreted as illustrative and not in a limiting sense.

I claim:—

1. A foldable means for holding and individually segregating a plurality of safety razor blades of the tongue-end type, comprising a strip of material foldable transversely to provide a plurality of interconnected blade holding sections upon which blades may be superimposed, said holding sections having widths in excess of the width of the blades to be received thereby, and each section having oppositely projecting end flaps having openings adjacent the line of fold thereof through which tongue-ends of said blades may project whereby said blades are secured against lateral displacement relative to holding sections to which they are applied.
2. A foldable means for holding and individually segregating a plurality of safety razor blades of the tongue-end type, comprising a strip of material foldable transversely to provide a plurality of interconnected blade holding sections upon which blades may be superimposed, said holding sections having widths in excess of the width of the blades to be received thereby, each section having oppositely projecting end flaps having openings substantially contiguous to the line of fold thereof through which tongue-ends of said blades may project so as to be secured against both lateral and longitudinal displacement relative to holding sections to which they are applied, and an external cover means connected with one end of said strip of material, said cover means comprising a main body, sidewise foldable flaps at each side of said main body, one of said sidewise foldable flaps being foldably connected to the end of said strip of material forming said blade holding sections, and endwise foldable flaps connected respectively with the opposite ends of said main body.
3. In testimony, that I claim the invention set forth above I have hereunto set my hand this 22nd day of April 1931.

PHILIP H. UNSINGER.
